United States Patent

Des. 240,789
Patented Aug. 3, 1976

240,789

DRINKING STRAW

Mitchell J. Frumkin, Chicago, Ill., assignor to Marvin
Glass & Associates, Chicago, Ill.

Filed Dec. 6, 1974, Ser. No. 530,227

Term of patent 14 years

Int. Cl. D7—06

U.S. Cl. D7—42

Fig 1

Fig 2

Fig 3

FIG. 1 is a perspective view of a drinking straw showing my new design;

FIG. 2 is a front elevational view, on an enlarged scale, of the drinking straw of FIG. 1;

FIG. 3 is a rear elevational view of the drinking straw;

FIG. 4 is a top plan view of the drinking straw;

FIG. 5 is a side elevational view of the drinking straw; and

FIG. 6 is a bottom plan view of the drinking straw.

The side opposite that of FIG. 5 is identical to that shown.

I claim:

The ornamental design for a drinking straw, as shown and described.
